UNITED STATES PATENT OFFICE.

RICHARD P. ELLIOTT, OF BOSTON, MASSACHUSETTS.

DESIGN FOR A FURNITURE-STANDARD.

SPECIFICATION forming part of Design No. 33,864, dated January 8, 1901.

Application filed December 13, 1900. Serial No. 39,786. Term of patent 14 years.

To all whom it may concern:

Be it known that I, RICHARD P. ELLIOTT, a citizen of the United States, residing at Boston, in the county of Suffolk and State of Massachusetts, have invented and produced a new and original Design for a Furniture-Standard, of which the following is a specification, reference being had to the accompanying drawing, forming part thereof.

10 The figure is a side elevation of a furniture-standard, showing my new design.

As shown in the drawing, the leading or material feature of my design consists of the upper straight portion *a*, which is tangent to the inwardly-curved portion *b* at the upper end thereof. Tangent to this inwardly-curved portion *b* at its lower end is the outwardly-

curved portion *c*. The upper straight portion *d* is tangent at its lower extremity to the inwardly-curved portion *e*, and this portion *e* is tangent at its lower extremity to the outwardly-curved portion *f*.

Having described my invention, what I claim as new, and desire to secure by Letters Patent, is—

25 The design for a furniture-standard, as herein shown and described.

Dated at Boston, Massachusetts, this 10th day of December, 1900.

RICHARD P. ELLIOTT.
